4 Claims. (Cl. 179—86)

The invention relates to a circuit arrangement for party line telephone systems, more particularly train control lines, in which the branch stations are called selectively from a main exchange or station.

In known arrangements of this kind the branch stations are selected from the main station transmission of impulse trains which actuate the step-by-step switching mechanism in all the branch stations, but puts the call through to the desired branch station only. This method of selective calling requires selectors of large capacity if, as is usual, a large number of stations are connected to the line, and it further requires a relatively large source of current in order to ensure the operation of the selectors. This arrangement is unsatisfactory for the further reason, that at each call from the main station all the selectors in the stations are operated and are subject to unnecessary wear, and, moreover produce an annoying noise. Furthermore the period necessary for a call to be completed is, in the known arrangements, relatively long; during this interval the stations are disconnected from the line, so that during this time no messages, not even urgent messages, can be transmitted to the main station.

Arrangements for the selective call of branch stations are already known which dispense with the use of selectors at the stations in which different frequencies to which the receiving relays in the subscribers' stations are tuned are used. These arrangements require that a large number of frequencies be provided. Other known arrangements which first mark a group of stations over the one or the other conductor of the party line by connecting battery potential and subsequently effect the individual selection by a transmission of different frequencies result in a reduction of the number of frequencies, but are not suitable for a large number of stations, moreover, these arrangements require the connection of earth potential at the station. The reverse arrangement, to effect at first group selection by means of predetermined frequencies and to effect the individual selection by means of direct current does not permit the increase of the number of subscribers beyond a certain limit, unless a large numbers of frequencies are again to be used. These arrangements also require the connection of earth potential at the station.

Furthermore it is already known, to effect selective calling of stations by means of high battery-potentials in combination with different

current directions and the use of separate circuits over the one or other conductor of the party conductors to earth. But also this arrangement can only be used for a limited number of stations, unless very large batteries are provided at the main station. Here again earth potential must be provided at the stations.

The present invention has the advantage over these known arrangements, that it permits the connection of a large number of branch stations and yet requires the provision of a small number of selecting frequencies in the exchange station and a small number of relays at the party-line stations. Moreover, it does not necessitate the provision of earth at the stations; this is of importance, if repeaters are to be used. This object of the invention is achieved in that a plurality of frequencies (for example two) are operative at the branch stations upon a number of receiving relays corresponding to the number of frequencies provided in voltage combinations corresponding with the desired branch station.

The drawing illustrates, by way of example, an embodiment of the invention. In Fig. 1 a party line GL is shown, comprising the main exchange or station A and a number of branch stations, of which only the stations T1, T2, and T3 are shown. The main station is provided with two sources of alternating current W1 and W2, W1 having a frequency of 15 Hz. and W2 a frequency of 100 Hz. The transformers Tr1 and Tr2 are tapped at various points so that different voltages may be tapped off. By the depression of the key provided upon the key board T for the desired stations an impulse consisting of the frequency-mixture of 15 Hz. and 100 Hz. of the requisite voltage combination as set out in Fig. 2 is supplied to the party line. Thus, for example, the station T1 is called by a frequency of 15 Hz. with a voltage of 10 v. and a frequency of 100 Hz. with a voltage of 100 v.; the station T2 is called by a frequency of 15 Hz. with a voltage of 20 v. and a frequency of 100 Hz. with a voltage of 90 v.; the station T3 is called by a frequency mixture of 15/100 Hz. and a voltage combination of 30/80 volt. The voltage combinations for calling the other stations are shown in Fig. 2.

The branch stations which are connected to the party line over transformers U1, U2, U3, etc. are each provided with two alternating current receiving relays R1, R2, of which the relay R1 is responsive to 15 Hz. and the relay R2 to 100 Hz. In view of the voltage drop upon the line these relays are associated in each station with series

resistances or potentiometers, not shown in the drawing in order to adjust the different voltages to the values of the respective stations. If, therefore, for example, the main station calls the station T3 by means of the key T3, the frequency 15 Hz. with a voltage of 30 v. and the frequency 100 Hz. with a voltage of 80 v. are received in the station T3. The two relays R1, and R2 of this station operate and connect the alarm WK at this station over the contacts r1 and r2. At the other stations one relay only is operated by the frequency mixture applied to the line during the call. In the stations T1 and T2 only the relays R1 are energised which are adjusted to an operating voltage of 10 and 20 v., respectively. The 15 relays R2 in these two stations cannot operate, as they are energised only by 100 and 90 v., respectively. In the branch stations T4 to T10 which are connected subsequent to the station T3 all the relays R2 operate, as these relays are adjusted to operating voltages below 80 v. The relays R1, however, cannot operate in these stations, as these relays require a voltage of more than 30 v. for their operation.

By an increase of the voltage or of the number of frequencies, or by both means jointly the number of combinations and hence the number of stations which it is possible to connect to the party line may be increased to any convenient limit.

I claim:

1. In a selective calling system, a line having a plurality of stations thereon, a plurality of sources of alternating current of different fre-

quency, and means for connecting said sources to said line in different voltage combinations one for each station, and relays at each station responsive to said frequencies of current at a particular voltage.

2. In a selective calling system having a plurality of stations connected to a line, means for connecting alternating current of two different frequencies to the line over different connections 10 to transmit current of different voltages, a relay at each of the stations responsive to one frequency but to different voltages thereof, and another relay at each station responsive to the other frequency but to different voltages thereof.

3. A system such as claimed in claim 2 wherein the relays at the stations along the line in one direction are responsive to progressively increasing voltages of one frequency while the other relays at the stations along the line in the same 20 direction are responsive to progressively decreasing voltages of the other frequency.

4. In a selective calling system, a line having a plurality of stations thereon, a plurality of relays at each station, each relay responsive to alternating current of a certain frequency and only above a certain voltage, a plurality of sources of alternating current, means for connecting said sources to the line via certain voltage taps, said sources when connected to the line via certain taps energizing all of the relays at 25 only one of said stations to thereby signal only that station.

BERNHARD SEIFFERT.
